UNITED STATES PATENT OFFICE.

IRVING W. MELCHER, OF PORTLAND, MAINE, ASSIGNOR OF ONE-HALF TO THEODORE C. WARE, OF SOUTH PORTLAND, MAINE.

COMBINED SWITCH-BOX AND VACUUM-LINE-SEAL MECHANISM FOR VACUUM-CLEANING SYSTEMS.

Application filed June 15, 1926. Serial No. 116,247.

My invention relates, in general terms, to vacuum cleaning systems and particularly to large installations where the exhauster is located in the basement and operates on several main lines extending throughout the building, with branch lines leading to a hose-attaching station in each of the several rooms,—as for instance, those in a hotel or office building.

One of the specific objects of my invention is to provide a proper hose-nozzle connection at each station whereby a quick attachment to and detachment from the units may be made, and operable so that but one length of hose may be required for all the several rooms located on one floor of the building,—unless it becomes necessary to operate in more than one room at any one time. Thus it is possible to economize on the cost of hose.

Another object is to provide means at each station so that the operator may have control of the electric circuit to start or stop the motor, so far as his particular station is concerned.

And a further and very important object relates to the feature incorporated in the device whereby after the disengagement of the hose-nozzle from any station unit, the electric circuit will automatically become broken and the opening to the vacuum pipe line be closed at that station.

The invention consists principally in an automatically functioning apparatus involving two distinct mechanical operations, eliminating the human element to put them in force, and is capable of fulfilling the foregoing objects and having characteristics which I will now describe in connection with one specific embodiment, which, at the present time, I consider preferable to other possible forms of the invention.

In the accompanying drawings in which like characters of reference designate similar parts throughout all the different views,—

Fig. 1 is a side elevation of the switch-box, in position within the wall of a room;

Fig. 2 is a front elevation of the switch-box;

Fig. 3 is a sectional elevation taken on line 3—3, Fig. 2, the seal member being in "closed" position;

Fig. 4 is a fragmentary elevation of the same, in section, taken on line 3—3, Fig. 2,—the seal being "open";

55

Fig. 5 is a plan view of the switch link shown connected to the arm of the seal, and

Fig. 6 is a diagrammatical lay-out of the electric circuit used in the system.

Fig. 1 illustrates one of the units permanently located at each station in a partition between two rooms, with the vacuum pipe line and the electric wires attached to the same.

In Fig. 3, which shows the parts in detail, 65 1 is the switch-box body, having a compartment 2 in which the electrical apparatus is housed, and another compartment 3 which serves as a vacuum chamber within which connection is made with the hose-nozzle 4—70 the partition 1' separating the two compartments.

On the face of the switch-box, at the open side, is a two-piece cover, attached to the box by the screws 5. One part of the cover, 6, closes the open side of the chamber 2 and the other part, 7, tightly fits and closes the chamber 3, except as hereinafter will be noted.

Mounted on the cover 7 and extending for 80 a spaced distance into the chamber 3, is a sleeve 8, with a slightly tapering bore 9. In this bore, 9, the hose nozzle 4 fits closely.

Secured in any convenient manner to the switch-box, and within the chamber 2, is an 85 ordinary snap-switch 10, and projecting from the body of the switch is a handle or arm 11. Engaging this arm is a link 12 pivotally secured at 14 to one end of the arm 13 of the seal 15,—the latter being 90 pivotally mounted on the cover portion 7, between the lugs 16. An opening 17 in the cover 7 allows the arm 13 to project through into the compartment 2.

The seal 15 is provided with a suitable 95 packing disc 18, which provides a tight joint when closed against the outer end of the sleeve 8.

Attached to the link 12, opposite its pivotally connected end 14, is a helical spring 19, 100 the latter being fixed to the switch-box at 20.

At the top and two sides of the switch-box 1 are openings 21, either one of which may be used to enter the cable 22 into the

compartment 2. The wires *a* and *b*, out of the cable, make proper connections with the switch at the binding posts 23.

At the lower end of the switch-box is a 5 boss 24, into which a branch 25 of the vacuum pipe line to the exhauster mains is screwed or otherwise secured.

Referring to Fig. 6, a diagrammatical layout of the electrical circuit is seen. The 10 motor 26 operates the exhauster or vacuum pump 27 with which is connected the usual intermediary elements, such as the receiver, dust bags, etc., common to all vacuum cleaning systems,—these latter not being shown 15 on the drawing.

The main lines of the circuit are represented by the character M, with the cable wires *a* and *b* connected therewith and operating in "parallel" and extending to the 20 various individual switches at each station in the boxes 1, 1,—these switches being shown in Fig. 6 as in "open" circuit.

It will be noted that any one of these 25 switches when "closed" will start the motor, provided it is not already in operation, and that so long as at least one of the stations is doing service the motor will continue to run.

In operation, the seal 15 is first raised 30 manually and held thus while the nozzle 4 is inserted in the sleeve 8, as seen in Fig. 4. The actuation of the seal member automatically acts to close the electrical circuit through the engagement of the link 12 with 35 the arm of the switch 11, and starts the motor rotating, if, as we will assume, this particular station is the only one operating in the system. Should others be operating the motor would, of course already be running, so the only effect will be to have the switch closed in case the others complete their work and throw off their switches previous to the completion of the work at 40 the station under consideration.

45 So it will be observed that the sole act by the operator to place a station in operation is to insert the nozzle, to which is attached the hose 28 and the cleaning implement at the end, (the latter not being shown) and proceed to do his cleaning work.

On the completion of his duty at this station, the operator withdraws the hose nozzle from the sleeve 8 and immediately the seal 50 drops, the spring 19 acting to force and yieldingly hold the seal over the opening in the sleeve, closing the vacuum pipe line at this station so as not to interfere with the operation of other units in the system which may be working.

60 This closing of the seal also breaks the electrical circuit and throws this particular switch "out", and should there be no other stations operating will cause the stoppage of the motor. In case, however, one or more 65 of the other stations are in service the action

occurring at the station under consideration will have no effect on the others, and, until such time as all of the units are idle and the nozzles withdrawn, the motor will continue to operate.

70 It is necessary to manually raise the seal when about to operate one of the stations, as it is obvious that the proper hose connection with the vacuum lines could not be made otherwise. From this point onward, 75 however, the operator ceases to be an essential factor in the functioning of the apparatus, as, after the nozzle is withdrawn the parts are automatically operated, whereas in some systems it is left to the operator to 80 throw out a switch, close the vacuum line or perform some other duty connected with the manipulation of the device, after his cleaning work has been performed.

85 My combined switch-box and vacuum line seal is particularly adapted for use in cleaning systems employing a large number of stations, as each unit is operable independently of all others and each may be put into service exactly as though it was the only 90 one in the building.

Mechanically, the device is simple in construction, effective in operation and is so designed as to present no disfigurement to the room in which it is installed.

95 And having thus described my invention, what I claim and wish protected by Letters Patent is:

1. In a device of the character described, comprising in combination with an electric 100 switch, a box having two compartments therein, a projection depending from said box and having an aperture therethrough extending into one of the said compartments, a cover on the said mentioned compartment, a sleeve on said cover having a bore therethrough, said bore communicating with the interior of said mentioned compartment, a seal pivotally mounted on said cover and adapted to act to open and to 105 close the said bore in said sleeve, and means in common to actuate said seal and said switch simultaneously.

110 2. In a device of the character described, a two-compartment box, a seal adapted to open and to close one of said compartments to the atmosphere, means to place said seal equipped compartment in communication with an atmospheric-pressure-reducing mechanism and means whereby said seal 115 may act to break an electric circuit when operating to close said compartment to the atmosphere and to close said circuit when operating to open said compartment to the atmosphere.

120 3. In a device of the character described, comprising in combination with an electric switch, a box having two compartments therein, said switch being operable in one 125 of said compartments, a sleeve in the other

of the said compartments having a bore therethrough, a flange on said sleeve adapted to partially close an opening in said second mentioned compartment, a hose nozzle fitting said bore in said sleeve, a seal adapted to open and close the passage through said sleeve, and means whereby the said seal may be actuated to close said opening in said sleeve simultaneously with the actuation of 10 said switch to open the electric circuit therethrough.

4. In a device of the character described, comprising in combination with an electric switch, a box having two compartments 15 therein, a projection on said box having an aperture therethrough, said aperture opening into one of the said compartments, a

sleeve having a bore therein communicating with the interior of said last mentioned compartment, a flange on said sleeve partially closing said last mentioned compartment on one side thereof, a nozzle adapted to fit said bore in said sleeve, a seal pivotally mounted on the flange of said sleeve, an arm on said seal, a link making pivotal connection with said arm and adapted to engage said electric switch, and means to force and yieldingly hold said seal in closed position with respect to the opening in said sleeve while said switch is being held by said link 30 acting to open the electric circuit through said switch.

IRVING W. MELCHER.
